FOUNTAIN TOOTHBRUSH

Harold Palmer Duey, Los Angeles, Calif.

Application November 8, 1939, Serial No. 303,414

8 Claims. (Cl. 15—138)

This invention relates to a fountain brush and particularly pertains to a tooth brush of the type embodying a reservoir in the handle thereof for a liquid dentifrice and including means for effecting delivery of the dentifrice from the reservoir to the bristles of the brush.

An object of the invention is to provide an efficient and conveniently operable means for dispensing the liquid dentifrice from the reservoir in the brush handle including a combined pump and valve structure and a manually operable means therefor arranged in the brush shank and interposed between the reservoir and the brush head.

Another object is to provide a construction in the brush head and in the combined pump and valve structure whereby the latter may be readily operated in a manner to effect delivery of the liquid dentifrice from the reservoir in the brush handle to the base of bristle tufts carried by the brush head.

Another object is to provide a combined pump and valve structure for a fountain tooth brush which is so formed and arranged as not to be subject to accidental operation thereby obviating unwanted discharge of dentifrice to the brush.

A further object is to provide a pump and tooth brush construction in which the liquid dentifrice acted on by the pump will be positively ejected in minute volumes by advancing of a pump piston in such fashion as not to flood the brush bristles yet afford adequate supply of the dentifrice whereby waste of the dentifrice may be avoided and economical use thereof insured.

With the foregoing objects in view, together with such other objects and advantages as may subsequently appear, the invention is carried into effect as illustrated by way of example in the accompanying drawing, in which:

Fig. 1 is a view in side elevation with a portion broken away of a tooth brush embodying the invention;

Fig. 2 is an enlarged detail in horizontal section taken on the line 2—2 of Fig. 1 showing the combined pump and valve structure;

Fig. 3 is a view in vertical section taken on the line 3—3 of Fig. 2 depicting the manner of operating the combined pump and valve structure;

Fig. 4 is a detail in inverted plan and partly in section as seen in the direction indicated by the arrows in Fig. 3;

Fig. 5 is a view in section taken on the line 5—5 of Fig. 1; and

Fig. 6 is a detail in cross section taken on 55

the line 6—6 of Fig. 3, showing the manner of directing the pumped dentifrice to the base of the bristle tufts.

Referring to the drawing more specifically 5 indicates a tubular tooth brush handle which is closed at one end by a demountable cap 9 and is fixedly connected at its other end to a shank 10 having a convergent outer end portion leading to and connecting with a tooth brush head 11. The cap 9 is formed with an externally threaded nipple 12 which is detachably screwed into engagement with internal threads 13 formed in the outer end portion of the tubular handle 8; the nipple 12 being formed with a passage 14 opening at the tip of the nipple to the interior of the handle and connecting with a valve chamber 15 formed in the cap 9 and in which chamber is disposed a ball check valve 16 normally seated on the inner margin of an air inlet 17 under the urge of a spring 18 bearing between the valve and a plug 19 constituting an end wall of the valve chamber 15.

The shank 10 constitutes a combined pump and valve housing and is formed at its enlarged end with a recess 20 bordered by an annular flange 21 which is fitted into the tubular handle 8 and is securely fastened thereto as by means of an adhesive or a cement. The reduced end of the shank 10 is formed with a transversely extending tongue 22 that is snugly fitted into a companion groove 23 formed on the inner end of the brush head 11; the tongue and groove being of dove-tail cross section whereby the parts are joined by sliding the tongue and groove lengthwise relative to each other into their inter-engaged position. The brush head is preferably detachably connected to the shank 10 by the dove-tail construction just described so as to permit interchange of brush heads when desired.

40 However the brush head and shank may be permanently fastened together by cementing the dove-tail joint. Extending axially through the shank 10 is a cylindrical bore 24 which opens at one end to the recess 20 and opens at its other end through the tongue 22, and which bore is formed of increased diameter at the end portion thereof leading into the recess 20 to form a cylinder 25 in which is mounted a pump piston 26 carrying a resilient valve 27 on one end thereof; the valve being arranged in the recess 20 and being adapted to seat on the bottom wall 28 thereof.

Leading from the recess 20 through its bottom wall 28 is a pair of parallel passages 29 and 30 which extend on opposite sides of the bore 24

and open into the latter through grooves 31 and 32 formed in the end face of the tongue 22; the ends of the passages in the recess 20 being covered and normally closed by the valve 27. These passages are quite small in diameter, so much so as to restrict the flow of liquid therethrough and prevent the free surging of liquid back and forth through the passages on operation of the pump piston as will hereinafter be fully described.

Reciprocation of the pump piston and the valve thereon is effected manually through the medium of a slide 33 located at the underside of the shank 10, which slide is mounted on a stem 34 connected to the side of the piston 26 intermediate the ends thereof through a slot 35 formed in the shank 10. The outer face of the slide 33 is serrated to afford a grip for a thumb or finger by which it is to be moved back and forth longitudinally of the shank in effecting operation of the pump and valve assembly.

The slide 33 is partly recessed within the shank 10 so that only the serrated face thereof will protrude from the outer face of the shank whereby the slide is protected and also guarded against being accidentally shifted.

The brush head 11 is formed with a central longitudinally extending bore 36 which is closed at its outer end and opens at its inner end at a point to register with the bore 24 in the shank 10 when the head and shank are assembled, the bore 36 extending between the base portions of parallel rows of bristle tufts 37. The base portions of the bristle tufts are wrapped in a binding 38 and are cemented in sockets 39 formed in the brush head in a conventional fashion. Diametrically opposite sides of the bore 36 intersect the sockets 39 through ports 40 from which passages 41 paralleling the base portions of the bristle tufts open to the latter at the juncture of the bristles with the face of the brush head from which they protrude.

In the operation of the invention a liquid dentifrice is placed in the tubular handle 8, the cap 9 being removed to admit placing of the liquid in the filler opening then afforded by the open end of the handle; the cap being replaced after loading the handle reservoir by screwing the threaded nipple 12 of the cap 9 into engagement with the threads 13 on the handle. The body of liquid in the handle will act by reason of the weight thereof to normally hold the valve 27 against its seat 28 thus obviating equipping the latter with spring closing means although there may be occasion where such spring closing means may be employed as by interposing an expandable spring 42 between the stem 34 and an end wall of the slot 35 shown in Fig. 3.

When it is desired to effect delivery of the liquid dentifrice, or a portion thereof, to the bristles 37, the brush is held with the head thereof lowermost and the slide 33 is engaged by a thumb or finger and is manipulated to effect reciprocation of the pump piston 26 movement of which is imparted to the valve 27 so that the valve is alternately retracted and advanced relative to its seat 28; the valve being moved away from its seat as the piston 26 is retracted and being moved toward its seat as the piston is advanced. Retraction of the piston 26 creates a suction in the cylinder 25, bores 24 and 36, grooves 31-32, passages 29-30, and to a slight extent in the passages 41 when the bore 36 is empty but to a negligible extent, if at all, when the bore 36 is filled with liquid. As this action of the piston starts, the valve 27 moves from its seat as indi-

cated by broken lines in Fig. 3 and thereby opens the passages 29-30 to the body of liquid dentifrice contained in the handle 8, so that the suction induced in the passages 29-30, coupled with head of liquid in the then up-ended handle, causes liquid to pass through the passages 29-30 and grooves 31-32 into the bore 24 and cylinder 25 and also into the bore 36 in event it be empty. On advance of the piston 26 liquid confined in the cylinder 25 will be forced therefrom into the bore 24 and thence into the bore 36 in the brush head, and when the cylinder 25, bores 24 and 36, grooves 31-32 and passages 29-30 are filled with the liquid advance of the piston will cause a portion of the liquid to pass through the ports 40 and passages 41 to the bases of the several bristle tufts 37.

In initial operation of the pump several reciprocations of the piston will be required in order to effect filling of the several spaces in the shank and brush head, but when such spaces are filled but one reciprocation of the piston will effect discharge of liquid to the bristles.

However, it is not essential that the spaces in the brush head and shank be completely filled in order to effect delivery of liquid to the bristles; since advance movement of the piston against air entrapped in the spaces will cause liquid confined in the bore 36 to flow to discharge through the ports 40.

The flow of liquid from the handle 8 to the passages 29-30 is facilitated by provision of the valved air intake 17 in the cap 9, in which the valve 16 will be unseated by outside air pressure on air pressure being reduced interiorly of the handle by displacement of liquid therein.

However it is desirable that the liquid shall not flow freely from the reservoir in the handle to the pump chamber, since such might occasion flooding of the brush, and accordingly such flow is prevented by reason of the restriction afforded by the smallness of the passages 29 and 30.

By provision of the construction set forth only a modicum of the liquid will be dispensed on a single operation of the pump, and on release of the slide 33 the valve 27 will come to rest on the seat 28 thereby closing the passages 29-30 and thus preventing leakage of liquid from the handle to the brush head. Closing of the passages 29-30 by the valve 27 relieves liquid therein of pressure, which with the minuteness of the discharge ports 40 and passages serves to hold the liquid confined in the spaces in the shank and brush head against leakage from the latter.

It should be noted that the passages 29 and 30 are of such small diameter and thereby so constricted that when the brush is held in a substantially upright position or in a vertical position, the pressure provided by the head of the liquid in the handle will prevent appreciable surging, that is, back flow of liquid through said passages; the liquid following the course of least resistance and thereby discharging through the multiplicity of ports 40 into the bristles.

I claim:

1. In a fountain tooth brush, a head having bristles thereon and a passage and ports therein through which liquid may be applied to said bristles, a tubular handle connected to said head and having its bore communicated at one end with said passage, a pump piston reciprocable in and dividing said bore so that the portion between the piston and the outer end of the bore may serve as a liquid reservoir and portion be-

tween said piston and said passage may serve as a pump barrel, means affording the introduction of liquid into the reservoir portion of said bore, said handle having a passage therein apart from said bore for by-passing liquid around said piston from the reservoir portion to the pump barrel portion of said bore, means for reciprocating the piston, and a valve member between the piston and the reservoir portion of the bore for controlling said by-pass passage responsive to the strokes of the piston.

2. In a fountain tooth brush, a head having bristles thereon and a passage and ports therein through which liquid may be applied to said bristles, a tubular handle connected to said head and having its bore communicated at one end with said passage, a pump piston reciprocable in and dividing said bore so that the portion between the piston and the outer end of the bore may serve as a liquid reservoir and portion between said piston and said passage may serve as a pump barrel, means affording the introduction of liquid into the reservoir portion of said bore, said handle having a passage therein apart from said bore for by-passing liquid around said piston from the reservoir portion to the pump barrel portion of said bore, means for reciprocating the piston, and a valve member carried on the outer end of the piston for controlling said by-pass passage.

3. In a fountain tooth brush, a head having bristles thereon and a passage and ports therein through which liquid may be applied to said bristles, a tubular handle connected to said head and having its bore communicated at one end with said passage, a pump piston reciprocable in and dividing said bore so that a portion thereof between the piston and the outer end of the bore may serve as a liquid reservoir and a portion thereof between said piston and said passage may serve as a pump barrel, means affording the introduction of liquid into the reservoir portion of said bore, said handle having a passage therein apart from said bore for by-passing liquid around said piston from the reservoir portion to the pump barrel portion of said bore, means for reciprocating the piston, and a valve member carried by the piston and disposed at the juncture of the reservoir and pump barrel portions of the bore for controlling said by-pass passage.

4. In a fountain tooth brush, a head having bristles thereon and a passage and ports therein through which liquid may be applied to said bristles, a tubular handle connected to said head and having its bore communicated at one end with said passage, a pump piston reciprocable in and dividing said bore so that the portion between the piston and the outer end of the bore may serve as a liquid reservoir and portion between said piston and said passage may serve as a pump barrel, means affording the introduction of liquid into the reservoir portion of said bore, said handle having a passage therein apart from said bore for by-passing liquid around said piston from the reservoir portion to the pump barrel portion of said bore, means for reciprocating the piston, a valve member between the piston and the reservoir portion of the bore for controlling said by-pass passage responsive to the strokes of the piston, and spring means operating through said piston for normally holding said valve closed.

5. In a fountain tooth brush, a head having bristles thereon and a passage and ports there-

in for conducting liquid to the bristles, a handle connected to the head and having an axial bore therein communicated directly at one end with one end of said passage, a pump piston reciprocable in and dividing said bore so that one portion of the bore serves as a pump barrel in direct communication with said passage and the remainder of the bore serves as a reservoir, said handle having a valve chamber between and communicated with the pump barrel and the reservoir portions thereof, said handle having a passage apart from said bore and leading from the valve chamber to the pump barrel portion of the bore for by-passing liquid around the piston, means for moving said piston, and a valve member carried by the piston and operating in said valve chamber for opening and closing said by-pass passage.

6. In a fountain tooth brush, a head having bristles thereon and a passage and ports therein through which liquid may be applied to said bristles, a tubular handle connected to said head and having its bore communicated at one end with said passage, a pump piston reciprocable in and dividing said bore so that a portion thereof may serve as a liquid reservoir and another portion may serve as a pump barrel, means affording the introduction of liquid into the reservoir portion of said bore, said handle having a passage therein apart from said bore for by-passing liquid around said piston from said reservoir portion to said pump barrel portion, means for reciprocating the piston, and a valve between the piston and the reservoir portion of the bore for controlling said by-pass passage responsive to the strokes of the piston, said by-pass passage being so constricted that when the brush is disposed in upright position the pressure produced by the head of the liquid therein will restrain back flow of liquid through the said by-pass passage.

7. In a fountain tooth brush, a head having bristles thereon and a passage and ports therein for conducting liquid to said bristles, a shank connected at one end to said head and having a bore therein in alignment and communication with said passage, said bore having a counter-bore between its ends forming a pump barrel, and also provided at the outer end thereof with another counter-bore forming a valve chamber, said shank having formed therein apart from said bores, a by-pass passage extending from the valve chamber through the end of the shank connected to the head, said last named end of the shank having a recess therein communicating the by-pass passage with the inner end of said bore at the outer end of the passage in the head, a pump piston in the pump barrel portion of said bore, a valve member fixed to the outer end of said piston for operation in said valve chamber to control said by-pass passage, a tubular handle member connected with the outer end of said shank in direct communication with said valve chamber and adapted to contain a liquid, means affording the filling of said tubular handle and means for operating said piston.

8. In a fountain brush, a head having bristles thereon and a passage and ports therein for conducting liquid to said bristles, a shank connected at one end to said head and having a bore therein in alignment and communication with said passage, said bore having a counter-bore between its ends forming a pump barrel, and also provided at the outer end thereof with another counter-bore forming a valve chamber, said

shank having formed therein apart from said bore by-pass passages extending from the valve chamber and along opposite sides of said bores through the end of the shank connected to the head, said last named end of the shank having recesses therein communicating the by-pass passages with the inner end of said bore at the outer end of the passage in the head, a pump piston in the pump barrel portion of said bore, a valve

member fixed to the outer end of said piston for operation in said valve chamber portion of the bore to control said by-pass passages, a tubular handle member connected with the outer end of said shank in direct communication with said valve chamber and adapted to contain a liquid, means affording filling of said tubular handle, and means for operating said piston.

HAROLD PALMER DUEY,
